UNITED STATES PATENT OFFICE.

GERRIT NORTON, OF NEW YORK, ASSIGNOR TO MATILDA NORTON, OF ITHACA, NEW YORK.

CORKING-MACHINE.

SPECIFICATION forming part of Letters Patent No. 391,760, dated October 23, 1888.

Application filed January 25, 1888. Serial No. 261,858. (No model.)

To all whom it may concern:

Be it known that I, GERRIT NORTON, of the city, county, and State of New York, have invented certain new and useful Improvements 5 in Corking-Machines, of which the following is a specification.

This invention relates to an improved machine for corking bottles, jars, and other vessels having mouths of different sizes; and the 10 invention consists of a corking machine comprising an upright supporting-frame, a vertically-reciprocating plunger, a lever fulcrumed to the frame and pivoted to the plunger-rod, said lever being provided with two anti-friction rollers, a vertically-reciprocating cork-pressing tube supported on a ring-shaped bracket guided in ways of the frame, a lever pivoted to said bracket and fulcrumed to the supporting-frame, said lever being provided 15 with anti-friction rollers, and a weighted cam-lever fulcrumed to the frame and operating a cam provided with projecting toes and intermediate arc-shaped portions by which the plunger and cork-pressing tube are operated 20 at the proper time, so as to force the cork into the mouth of the bottle or jar and retain the latter by a fixed guard-plate below the cork-pressing tube, as will appear more fully hereinafter, and finally be pointed out in the claims. 25

In the accompanying drawings, Figure 1 represents a side elevation of my improved corking-machine. Fig. 2 is a side elevation of the upper part of the same, showing the working parts on a larger scale. Figs. 3 and 4 30 are a horizontal section of the bottle-guard on line $x-x$, Fig. 2, and a vertical section of the same; and Fig. 5 is a vertical central section of a cork-pressing tube for a large-mouthed bottle or jar.

Similar letters of reference indicate corresponding parts. 35

Referring to the drawings, A represents an upright supporting-frame, of cast metal or other suitable material, which is provided at its upper part with three fulcra, a a' a'' , which are arranged vertically below each other. 40

A weighted operating-lever, B, and a cam, C, are keyed to the middle fulcrum, a' , the cam C being provided with three projections or toes, b b' b'' , and intermediate arc-shaped steady- 45 portions d d' d'' , which serve to impart mo-

tion to the different operating parts of the machine.

To the upper fulcrum, a , is applied a lever, D, which is pivoted by its slotted outer end 55 to the upper end of the plunger-rod E, which is guided in a fixed sleeve, e, of the frame A. The plunger-lever D is provided with two anti-friction rollers, f f' , one at each side of the fulcrum a , which are engaged, respectively, by 60 the toes b b' and steadyng portion d , according as the plunger is lowered or raised by the action of the cam C.

Vertically below and in line with the axis of the plunger E is arranged a conical cork-pressing tube, F, which is supported in a ring-shaped bracket, F', that is made integral with a grooved slide-piece, F'', which is guided on a fixed dovetail-shaped rail, g, of the frame A and pivoted to a lever, G, that is applied to 65 the lower fulcrum, a' , and provided like the lever D with two anti-friction rollers, g g' , one at each side of the fulcrum a' , that are acted upon by the toes b'' and the arc-shaped steadyng portions d' d'' of the cam C, as shown clearly 70 in Fig. 2, according as the operating-lever B is raised or lowered. The conical cork-pressing tube F is provided at its lower end with a tubular extension, f', which projects through an opening of a stationary guard-plate, H, that 75 is attached to the frame A, below the slide-piece F''. For corking vessels having mouths of different sizes, different sizes of cork-pressing tubes are used, which tubes are inserted into the ring-shaped bracket F' and secured 80 thereto by a suitable set-screw, f'', or other fastening device.

Cork-pressing tubes F, having different sizes of interior openings, may be used in connection with the ring-bracket F', as shown in 85 Figs. 2 and 5, according to the mouths of the bottles or jars to be corked. The guard-plate H is provided with a ring-shaped opening of sufficient size for the passage of the tubular extensions f' of the different cork-pressing tubes F. The guard-plate H is further provided at its under side with an interchangeable plate, H', the opening of which corresponds to the size of the extension-tube f', said plate H' being guided in ways h of the guard- 90 plate, as shown in Figs. 2, 3, and 4.

For operating my improved corking-ma-

chine, the bottle or jar to be corked is placed below the stationary guard H, the tubular lower end of the cork-guiding tube being inserted into the mouth of the bottle or jar, as shown in Fig. 1. The cork is then placed into the conically-flaring upper portion of the tube F. The operating-lever B is then lowered by hand or steam power, which produces first the lowering of the plunger by the action of the toes b b' of the cam C on the anti-friction rollers f f' of the plunger-lever, so that the cork is forced downwardly through the tubular extension f' of the tube F into the mouth of the bottle or jar. Simultaneously with this motion the cork-pressing tube F and its bracket F' are raised by the action of the toe b' of the cam C on the fulcrumed lever of the bracket F', and the latter thereby moved away from the mouth of the bottle or jar as the cork is forced in the same, until the tubular extension f' clears entirely the mouth of the bottle and the cork in the same, which is thus transferred to the mouth of the bottle or jar. By lifting the operating lever the plunger and cork-pressing tube are returned by the action of the cam and lever into their normal positions, being then ready for the next corking action, and so on.

Having thus described my invention, I claim as new and desire to secure by Letters Patent—

1. The combination of a vertically-reciprocating plunger, a vertically-guided cork-pressing tube having tubular extension, a stationary guard-plate below said tube, and means for reciprocating the plunger and cork-pressing tube, substantially as set forth.

2. The combination of a vertically-reciprocating plunger, a vertically-reciprocating cork-pressing tube, a ring-shaped and guided bracket for said tube, a stationary guard-plate below said tube, fulcrumed levers pivoted, respectively, to the plunger-rod and the slide-piece of the bracket, an operating-lever fulcrumed to the supporting-frame, and a cam keyed to the fulcrum of the operating-lever and provided with toes and steadyng portions for actuating the plunger and cork-pressing tube, substantially as set forth.

3. The combination of a vertically-reciprocating plunger, a cork-pressing tube having a

tubular extension, a vertically-reciprocating bracket-ring supporting the cork-pressing tube, a stationary guard-plate located below said tube and provided with an opening for said extension, fulcrumed levers pivoted to the plunger-rod and bracket, an operating-lever, and a cam keyed to the fulcrum of said operating-lever, said cam actuating the plunger and cork-pressing tube, substantially as set forth.

4. The combination of a supporting frame, a cork-pressing tube, a ring shaped bracket for supporting the cork-pressing tube, a slide-piece for said bracket guided on the supporting-frame, a fulcrumed lever pivoted to said slide-piece, and an operating-lever and a cam keyed to the fulcrum of the operating-lever and provided with a projecting toe and arc shaped steadyng portions at each side of said toe, substantially as set forth.

5. The combination of a vertically-reciprocating plunger, a vertically - reciprocating cork-pressing tube having a tubular extension, means for actuating the plunger and tube, and a stationary guard-plate below said cork-pressing tube, said guard-plate having an opening and an interchangeable plate guided in ways of the guard-plate, substantially as set forth.

6. In a corking-machine, a stationary guard-plate having an opening, and a detachable plate having an opening corresponding in size to the lower end of the corking-tube, said detachable plate being guided in ways of the stationary plate, substantially as set forth.

7. The combination of a vertically-reciprocating plunger, a cork-pressing tube, a vertically-reciprocating bracket-ring for said tube, means for fastening the cork-pressing tube to the bracket-ring, and a stationary guard-plate below the cork-pressing tube, the guard-plate being provided with a detachable plate guided in ways of the guard-plate, substantially as set forth.

In testimony that I claim the foregoing as my invention I have signed my name in presence of two subscribing witnesses.

GERRIT NORTON.
